ELECTRIC SANDWICH TOASTER

Peter G. Pritz, Jenkintown, Pa.

Application February 26, 1957, Serial No. 45,002

Term of patent 7 years

(Cl. D81—19)

Fig. 1.

Fig. 2.

Fig. 3.

Fig. 1 is a front elevation of the electric sandwich toaster; Fig. 2 is a top plan view of the same; and Fig. 3 is an end elevation of the same.

The back of the toaster is plain.

I claim:

The ornamental design for an electric sandwich toaster, as shown and described.
